UNITED STATES PATENT OFFICE.

BENJAMIN C. KREINER, OF WASCOTT, WISCONSIN.

SWITCH-LOCK.

1,187,338.

Specification of Letters Patent. Patented June 13, 1916.

Application filed January 8, 1915. Serial No. 1,168.

To all whom it may concern:

Be it known that I, BENJAMIN C. KREINER, a citizen of the United States, residing at Wascott, in the county of Douglas and State of Wisconsin, have invented certain new and useful Improvements in Switch-Locks; and I do hereby declare the following to be a full, clear, and exact description of the invention, such as will enable others skilled in the art to which it appertains to make and use the same.

My invention relates to new and useful improvements in switches provided with locking means to prevent closing thereof and the invention resides in the provision of a simple and inexpensive device of this character that is particularly designed for use in connection with automobiles and is arranged to be operated by a specially designed key.

Another object is to provide a switch of the character described in which the contact portions thereof are normally spaced from one another and cannot be moved into contacting engagement with each other without using a specially designed key.

Another object is to provide a device of the character described that employs a two part key that is constructed so that the parts are movable relative to one another and will operate to close the switch in a reliable and expeditious manner.

Another object is to provide a switch lock of the character described that may be constructed of few parts, that may be readily assembled and disassembled, which is small and capable of being readily attached upon the foot board or some other suitable place of an automobile or like vehicle and is inexpensive to manufacture.

The above and additional objects are accomplished by such means as are illustrated in the accompanying drawings, described in the following specification and then more particularly pointed out in the appended claims.

With reference to the drawings, wherein I have illustrated the preferred embodiment of my invention as it is reduced to practice, and throughout the several views of which similar reference numerals designate corresponding parts: Figure 1 is a side elevation of my improved switch lock with the cover plate removed showing the mechanism in locked position and the contact plates of the switch out of engagement with

each other, Fig. 2 is a view similar to Fig. 1 showing the switch closed and the mechanism unlocked, Fig. 3 is a front elevation partly broken away showing the switch closed, Fig. 4 is a transverse sectional view taken on line 4—4 of Fig. 1, Fig. 5 is a vertical sectional view taken on line 5—5 of Fig. 1, Fig. 6 is a detail perspective view of the locking mechanism supporting plate, Fig. 7 is a detail side elevation of the key, Fig. 8 is a detail perspective view of one of the elements of the key, Fig. 9 is a detail perspective view of the other parts of the key, Fig. 10 is a detail side elevation of the latch plate, Fig. 11 is a detail side elevation of the switch operating bolt, and Fig. 12 is a detail view of the operating lever for one of the contact plates.

Referring to the drawings by characters of reference, the numeral 1 designates as an entirety a rectangular casing equipped with a porcelain base 1^a and provided with a removable closure plate 2, on one side. Pivotally mounted within the casing 1 adjacent the upper and lower ends thereof are contact plates 3 and 4 that are preferably of copper and arranged so as to contact but are normally spaced from one another. A retractile spring 5 is secured at one end to the intermediate portion of the pivoted contact plate 4 and to a lug 6 carried by the casing and normally holds said contact plate in an angular position out of engagement with the contact plate 3. An expansion spring 7 is secured to a lug 8 on the casing at one end to the intermediate portion of the plate 3 and disposed to the plate 3 normally similarly to the one 4. These plates 3 and 4 are to be connected with the electrical conductors, not shown, and serve as a switch.

Mounted within the casing is an angular plate operating mechanism supporting plate designated 9 as an entirety. This plate is secured by screws 10 flatly upon one face of the casing 1. The plate 9 is provided with spaced lugs 11 arranged in pairs to form a guide for an elongated switch operating bolt 12 that is slidably mounted upon the plate 9 and extends between the pivot points of the switch plates 3 and 4. This switch operating bolt 12 is formed at its ends with lateral projections 13 and 14 that are both upon the same face of the bolt. The face of the projection 14 opposed to the projection 13 has mounted thereon a strip

of insulation 15 and is designed to coöperate with the free end of the contact plate 4. The contact plate 4 is provided upon the face thereof opposed to the insulation 15 with an insulation strip 16 which strip extends over and upon the end of the plate and is flush with the opposed side thereof. The projection 14 engages the insulation 16 on the plate 4 and provides means for moving the plate 4 into operative position.

The projection 13 extends above the upper edge of the bolt and is provided upon the face thereof opposed to the insulation strip 15 and at the lower end of said face with a projection or stop 17 that is designed to coöperate with a key which will be later and more fully described. A lug 18 also acting as a stop and extending at right angles to the one 17 is carried on the under part of the bolt 12 and is designed to limit the movement of said bolt in one direction. An expansion preferably helical spring 19 is secured at one end to a lug 20 on the plate 9 and at its other end to the outer face of the projection 13 on the bolt 12. This spring tends to force the bolt 12 to the left. The projection or stop 18 engages the adjacent one of the lugs 11 and thus limits the movement of the bolt 12.

Pivoted as at 21 to the lower part of the plate 9 is a contact operating lever 22 that extends upwardly normally at right angles to the bolt 12. The upper end of the lever 22 on one side thereof is provided with a strip of insulation 23 that is designed to engage a strip 24 similar to the one 16 but that is carried on the plate 3. This lever 22 is designed to engage and move the plate 3 into coöperative engagement with the plate 4. Pivoted as at 25 upon the plate 9 above the bolt 12 is a guard latch plate 26 that is provided upon its lower face with a recess 27 opening on said lower face and having one side cut away or beveled adjacent to said recess as at 28. An expansion spring 29 secured at one edge to a lug 30 on the plate 9 and at its other end adjacent to the free end of the plate 26 normally holds said guard and latch plate in proper position.

The plate 2 for closing the casing is provided with a key hole not shown and is designed to receive a key designated 31 as an entirety. This key 31 is especially designed for use in connection with my switch and consists of two coöperative and relatively movable parts 32 and 33, or better described as switch bolt operating and contact lever operating keys. With particular reference to Figs. 7, 8 and 9 wherein I have illustrated detail views of my improved key, it will be seen that the numeral 34 designates the tubular portion of the part 32 of the key and 35 and 36 projections extending at right angles to the body 34 and

formed integral therewith. Each of the projections is provided with a right angular extension or projection 37 which extends beyond the end of the body portion a slight distance. The part 33 of the key 31 consists of a relatively small preferably cylindrical body portion 38 that is inserted through the tubular body portion 39 and bent to provide a right angular extension 39 at one end. This extension 39 and the one 36 provide operating handles for the key. A right angular and relatively large extension 40 is formed on the other end of the body 38 and is similar in construction to the extension 35. The extensions 40 and 35 are arranged to move the elements of the mechanism so that the contact of the plates 3 and 4 is made. It will thus be seen that the elements constituting the key are movable relative to one another.

The operation of my device may be briefly described as follows: Assuming that the switch is open and the mechanism in position as illustrated in Fig. 1, the key 31 is inserted through the key hole in the plate 2 with the extension on the member 33 in upright position. The extension 40 engages within the recess 27 and thus the portion 33 of the key is held against rotation by having the portion 40 engage the opposed sides of the recess 27. The next step in the operation is to turn the element 32 of the key so that the portion 37 on the extension engages and moves the lever 22, passes the lever and then engages the cut away or beveled face 28 on the latch and guard plate 26. This portion 32 is moved approximately 90 degrees and when it engages the beveled face 28 the plate 26 is moved upwardly and releases the extension 40 on the element 33. The element 33 is then turned to the right, that is, in a clockwise direction after being released from the plate 26 until the portion 40 is brought to engage the opposed face of the extension 13 on the bolt 12. Further movement of the element 40 in a clockwise direction serves to move the bolt 12 to the right against the tension of the spring 19. The movement of the bolt 12 to the right moves the contact plate 4 into approximately vertical position and closer to the plate 3. When the plate 26 is moved into position the portion 37 of the element 32 of the key is in the position as shown in Fig. 2 and is moved from such position into an approximately horizontal position in a counterclockwise direction so as to engage and force the lever 22 outwardly thus causing the plate 3 to move into contacting engagement with the plate 4.

It will be readily seen with reference to the foregoing description and accompanying drawings that I have provided a simple and effective switch that will only operate in connection with my improved and

specially designed key. Should a key of the ordinary type be inserted in the key hole to operate the device it would engage in the recess 27 in the plate 26 and be prevented from movement.

To lock the device, that is open the switch, the extension 40 is moved into normal position, that is into alinement with the key hole from horizontal position as shown in Fig. 3 and the extension 35 is moved in a counterclockwise direction until it registers with and is disposed within the recess 27 in the plate 26. The key may then be withdrawn.

It will be noted that I have provided a device that may be readily and easily operated so that an electric circuit is opened and closed as desired and which is constructed so as to prevent unauthorized persons not equipped with a special key from operating the device. Further, knowledge of the manner of using the key must be had before a successful operation of the device may be gotten.

In practice, I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. In a device of the character described, a casing, contact plates pivoted within the casing and normally spaced from each other, a switch bolt slidable within the casing and having projections at each end, one of the projections engaging one of the contact plates and arranged to move the same into operative position, a pivoted contact plate lever within the casing arranged to engage the other of the contact plates to move it into position, a spring normally forcing said bolt into retracted position and means positioned between the lever and other of the projections on the bolt to move the lever and bolt in opposite directions whereby the contact plates engage each other.

2. In a device of the character described, a casing, contact plates pivoted within the casing and normally spaced from each other, a switch bolt slidable within the casing and having projections at each end, one of the projections engaging one of the contact plates and arranged to move the same into operative position, a pivoted contact plate lever within the casing arranged to engage the other of the contact plates to move it into position, a spring normally forcing said

bolt into retracted position, means positioned between the lever and other of the projections on the bolt to move the lever and bolt in opposite directions whereby the contact plates engage each other, and a latch plate pivoted above said bolt and having a recess opening on its under edge disposed between said last named projection and the lever to receive a key and prevent the same from moving the bolt.

3. In a device of the character described, a casing, contact plates pivoted within the casing and normally spaced from each other, a switch bolt slidable within the casing and having projections at each end, one of the projections engaging one of the contact plates and arranged to move the same into operative position, a pivoted contact plate lever within the casing arranged to engage the other of the contact plates to move it into position, a spring normally forcing said bolt into retracted position and means positioned between the lever and other of the projections on the bolt to move the lever and bolt in opposite directions whereby the contact plates engage each other, said means consisting of a key comprising relatively movable parts.

4. In a device of the character described, a casing, contact plates pivoted within the casing and normally spaced from each other, a switch bolt slidable within the casing and having projections at each end, one of the projections engaging one of the contact plates and arranged to move the same into operative position, a pivoted contact plate lever within the casing arranged to engage the other of the contact plates to move it into position, a spring normally forcing said bolt into retracted position, means positioned between the lever and other of the projections on the bolt to move the lever and bolt in opposite directions whereby the contact plates engage each other, and a latch plate pivoted above said bolt and having a key engaging recess opening on its under edge disposed between said last named projection and the lever and said last named means consisting of a key formed of two relatively movable parts to respectively move the lever and engage the last named projections and move the bolt in the opposite direction.

5. In a switch lock the combination with a casing of pivoted contact members mounted within the casing and normally spaced from each other, a switch bolt slidable within the casing and arranged to move one of said contact members into operative position, a lever pivoted within the casing and arranged to move the other of the contact members into position where it will engage the first named contact member, said lever being positioned intermediate the ends of the bolt, relatively movable members positioned between the lever and one end of the

- 4
- 5 bolt; and having projections arranged to engage the lever and the bolt to move them in opposite directions to bring the contact members into engagement with each other.
  - 6. In a switch lock the combination with a casing of pivoted contact members mounted within the casing and normally spaced from each other, a switch bolt slideable within the casing and arranged to move one of
  - 10 said contact members into operative position, a lever pivoted within the casing and arranged to move the other of the contact members into position where it will engage the first named contact member, said lever being
  - 15 positioned intermediate the ends of the bolt, relatively movable members positioned be-

tween the lever and one end of the bolt, and provided with projections arranged to engage the lever and bolt to move them in opposite directions to bring the contact members into engagement with each other and means to hold one of the movable members against movement and arranged to release said member upon the movement of said other relatively movable member in a 25 certain direction.

In testimony whereof I affix my signature in presence of two witnesses.

BENJAMIN C. KREINER.
